United States Patent Office.

SAMUEL S. BENT, OF PORTCHESTER, NEW YORK.

Letters Patent No. 78,044, dated May 19, 1868.

IMPROVEMENT IN CHICKEN-COOPS.

The Schedule referred to in these Letters Patent and making part of the same.

TO ALL WHOM IT MAY CONCERN:

Be it known that I, SAMUEL S. BENT, of Portchester, Westchester county, State of New York, have invented, made, and applied to use a certain new and useful Improvement in Chicken-Coops; and I do hereby declare the following to be a full, clear, and exact description of the said invention, reference being had to the annexed drawing, making part of this specification, wherein—

Figure 1 is a perspective view of said coop complete and in use.

Figure 2 is a section through the doors, or slide for the chicken.

Similar marks of reference denote the same parts.

In raising poultry, losses frequently occur by foxes, rats, and weasels getting into the chicken-coop, and killing the young chickens. To secure the chicken-yard against these intruders is almost impossible, besides which it is usual to keep the different broods separate by placing the hen in a small separate coop, and allowing the chicken to pass into and out of that coop.

When the breeding-season has passed, these separate coops occupy considerable space, and, consequently, are usually left exposed to the weather, and become rotten and broken.

The nature of my said invention consists in a metallic open-work end-piece for a chicken-coop, formed with openings that are large enough for the chickens to pass through, which openings are provided with sliding doors or covers, connected together, so as to be operated simultaneously.

The other portion of the metallic plate is formed with openings sufficient for ventilation, but of a size so small that no rats or other animals can get through to injure the chickens; hence the respective broods will be securely protected by simply closing the sliding doors before leaving the chickens for the night. This is done with ease and rapidity, even by a child.

In the drawing, *a* is the metallic plate, forming the end of the coop. There may be a similar plate at each end, or such plate may form the side of the coop. I, however, prefer to employ the end-plates, as shown, one having a door, *b*, through which the hen is introduced.

A flange, *m*, at the inner angles of the plate *a*, at each side, serves for fastening the side-boards *c c* to the metallic ends *a* by screws and similar flanges *d d*, and screws or screw-bolts answer for securing the lapped roof-boards *e e*.

A bottom board may also be attached, if desired, or the coop may sit upon the ground.

The upper portion of the plate *a* is to be formed with small openings, of any desired shape. The design of the ornamental shape of these openings does not form any part of this portion of my invention.

In the lower part of the plate *a* are openings *i i*, of a suitable size for the chicken to go freely through them, and *h h* are doors, for covering these openings at night. These doors are connected together, and form a sliding plate, that is moved with facility by the knob *l* or handle.

When these coops are not in use, they may be taken apart with rapidity, and packed into a small space for use the next season.

What I claim, and desire to secure by Letters Patent, is—

A chicken-coop, formed with an open-work metallic plate, in the lower portion of which there are openings, closed, when desired, by a range of doors or covers, substantially as and for the purposes set forth.

In witness whereof, I have hereunto set my signature, this fourteenth day of April, 1868.

SAMUEL S. BENT.
